UNITED STATES PATENT OFFICE

132,112

DESIGN FOR A GREETING CARD OR SIMILAR ARTICLE

Ernest D. Chase, Winchester, Mass.

Application December 26, 1941, Serial No. 104,859

Term of patent 7 years

To all whom it may concern:

Be it known that I, Ernest D. Chase, a citizen of the United States, residing at Winchester, in the county of Middlesex, State of Massachusetts, have invented a new, original, and ornamental Design for a Greeting Card or Similar Article, of which the following is a specification, reference being had to the accompanying drawing, forming part thereof, in which the figure is a plan view of a greeting card or similar article showing my design.

I claim:

The ornamental design for a greeting card or similar article, as shown.

ERNEST D. CHASE.
